UNITED STATES PATENT OFFICE.

JAMES ROSS CROZIER AND ROBERT J. CROZIER, OF ELMORE, OHIO.

FURNACE.

1,295,275.

Specification of Letters Patent. Patented Feb. 25, 1919.

Application filed June 6, 1916. Serial No. 102,012.

To all whom it may concern:

Be it known that we, JAMES R. CROZIER and ROBERT J. CROZIER, citizens of the United States, residing at Elmore, in the county of

5 Ottawa and State of Ohio, have invented new and useful Improvements in Furnaces, of which the following is a specification.

This invention relates to furnaces, and it has particular reference to a furnace of the 10 hot air type which is equipped with a fire pot in which water may be heated for the purpose of circulating the same through a radiating system.

The invention has for its object to produce 15 a furnace in which a stack or series of drums are supported on the fire pot for the circulation of the products of combustion, said drums being open at the ends thereof for the passage of air which may thus be 20 heated.

A further object of the invention is to simplify and improve the construction and arrangement of those parts of the furnace casing which coöperate with the drums to 25 produce the space for the circulation of the products of combustion.

With these and other ends in view which will readily appear as the nature of the invention is better understood, the same 30 consists in the improved construction and novel arrangement and combination of parts which will be hereinafter fully described and particularly pointed out in the claim.

In the accompanying drawings has been 35 illustrated a simple and preferred form of the invention, it being, however, understood that no limitation is necessarily made to the precise structural details therein exhibited, but that changes, alterations and modifications 40 within the scope of the claim may be resorted to when desired.

In the drawings,—

Figure 1 is a side elevation of a furnace constructed in accordance with the invention.

Fig. 2 is a front end view of the same.

Fig. 3 is a rear end elevation.

Fig. 4 is a vertical sectional view taken on the line 4—4 in Fig. 2.

50 Fig. 5 is a transverse sectional view taken on the line 5—5 in Fig. 1.

Fig. 6 is a perspective view showing the two parts or members of one of the drums separated from each other.

55 Fig. 7 is a top plan view of a furnace with the top plate or cap plate removed.

Fig. 8 is a perspective view of the fire pot showing the supporting plate connected therewith.

Corresponding parts in the several figures are denoted by like characters of reference.

The fire pot 15 which is supported on the ash pit casing 16 is made hollow to form a water compartment 17 having at each side 65 thereof an inlet 18 and an outlet 19 which may be connected with a circulating system. By this construction of the fire pot the water for a hot water system may be heated very effectively and inexpensively.

70 The fire pot is constructed with a recess 20 constituting a fuel intake, and the top of the fire pot supports a plate 21 which, if desired, may be in the nature of a flange which is integral therewith, said plate or flange 75 serving as a support for the superposed hot air drums. Each of said drums is composed of two parts or members B, C. The members B and C are of substantially similar construction, but the members C are inverted upon the members B. Each of said members is composed of a substantially flat plate 22, the front and rear ends of which are curved to produce flanges 23, the flanges of the member B being projected upwardly, 80 while the flanges of the members C are projected downwardly, as will be readily understood by reference to the drawings, the meeting edges of the flanges being, moreover, provided with grooves and tongues 24, 25 85 so that tight joints will be formed between the members when they are assembled. The side edges of the members B and C are provided with vertical flanges 26 which extend downwardly with respect to the plates 22 of 90 the members B and upwardly with respect to the plates 22 of the members C.

When the two members B and C are assembled together they will virtually constitute an elongated tubular drum, the ends of 100 which are provided with lateral flanges, the top and bottom edges of which are straight and parallel, the end edges of said flanges being, likewise, straight and substantially at right angles to the top and bottom edges. 105 Any desired number of these drums may be used, the bottom drum being supported on the plate or flange 21 resting on the fire pot, and the remaining ones being superposed on the bottom one. In the drawings three such 110 drums have been shown, but the number may obviously be varied. The furnace front con-

sists of a plate 27 which is suitably connected with the front ends of the drums by means of bolts or the like, the manner of connecting the parts together differing in no essential way from that which is usually employed in the construction of stoves and furnaces, it being also understood that tongue and groove joints are to be employed wherever needed and that care is to be taken to 10 make the construction smoke proof. The front plate 27 has a door 28 through which access may be had to the interspaces between the tubular portions of the drums in order that such spaces may be conveniently 15 cleaned. Another door 29 is provided through which access may be had to the fire pot for the purpose of feeding the fire. Still another door 30 provides access to the ash pit, said door being constructed with a draft 20 opening obstructed by a damper 31. The fire pot is provided with a shaking grate 32, the shank of which 33 may be reached through a door 34 generally known as the clinker door.

25 Connected with the drums at the rear ends thereof is the back plate 35 which affords a tight closure for the rearward ends of the interspaces between the tubular portions of the drums. A cap plate 36 is also provided, 30 the same having a smoke outlet 37. The intermediate unit of the drum has the rounded ends of its horizontal plates spaced from the front as well as from the back plate, the outer drum units having their forward ends 35 contacting with the front plate. On the intermediate and top units of the drum are arranged dampers 39 provided with operating rods 40 which extend through the front plate. The upper drum unit has arranged 40 upon the upper face thereof ribs 38 that serve as stops for the damper.

Assuming that the dampers are in their open position, the products of combustion from the fire box will be permitted to pass 45 direct between the back 35 and the rear ends of the rounded portions of the drum units, this being the path of least resistance. When the damper for the intermediate drum unit

is closed, as illustrated in Fig. 4 of the drawings, the products of combustion will be compelled to take a circuitous path, traveling first to the rear of the lower drum unit, then between the lower and intermediate drum units, around the front of the intermediate drum unit, over the top thereof, beneath the bottom of the uppermost drum unit and thence to the smoke exit. The flow of the products of combustion from the fire pot to the smoke outlet may be regulated by adjusting the upper damper 39.

Having thus described the invention, what is claimed as new, is:—

The herein described construction of furnace, comprising an ash pit casing, a fire pot resting thereon, a horizontal plate formed on the outer edge at the top of the fire box and extending beyond the sides and ends thereof, a front plate and a back plate secured to the opposite edges of said horizontal plate, a drum resting on the horizontal plate and connected to the front and back plates, said drum comprising a plurality of superimposed units each comprising two sections, each of said sections embodying horizontally disposed plates having their ends rounded toward each other and having a tongue and groove connection at their said ends, and side plates extending from the inner edges of the said horizontal plates and the rounded ends thereof, the contacting edges of the side plates of the respective units of the drum having tongue and groove engagement, a cap plate resting upon the uppermost drum unit and secured thereto, an integrally formed smoke outlet on said cap plate, and dampers between certain of the units of the drum and the back plate of the furnace.

In testimony whereof we affix our signatures in presence of two witnesses.

JAMES ROSS CROZIER.
ROBT. J. CROZIER.
